E. G. THOMAS

TESTING DEVICE

Filed Sept. 29, 1924

UNITED STATES PATENT OFFICE.

EDWARD G. THOMAS, OF TOLEDO, OHIO, ASSIGNOR TO TOLEDO SCALE COMPANY, OF TOLEDO, OHIO, A CORPORATION OF NEW JERSEY.

TESTING DEVICE.

Application filed September 29, 1924. Serial No. 740,484.

This invention relates to testing devices, and more particularly to devices for testing the weight per unit of length of a strip of coated fabric or other material. It is desirable that coated fabrics and similar products be of uniform weight, and calendering machines are commonly provided with means whereby the weight of the coating may be increased or decreased. In the coating or impregnating of the majority of fabrics, the rolls of the calendering machine are heated and as the coated fabric comes from the machine the coating is hot and plastic and has a tendency to adhere to the rollers of the testing device, thereby increasing the weight of the rollers and resulting in an error in the indication.

One of the principal objects of this invention is the provision of effective means for preventing the soft and plastic coating from adhering to the rollers of the testing device.

Another object of this invention is the provision of a roller embodying self-contained heating elements, thus decreasing the liability of an accidental fire and insuring even heating of the roller.

Still another object of the invention is the provision of a heated roller for a testing device which is simple in construction and inexpensive to manufacture and which requires little attention when in operation.

Other objects and advantages will be apparent from the following description, in which reference is had to the accompanying drawings illustrating preferred embodiments of my invention and wherein similar reference numerals designate similar parts throughout the several views.

In the drawings:—

Figure I is a fragmentary elevational view of a testing device embodying one form of my invention;

Figure II is an enlarged sectional view through a portion of the roller, taken substantially on the line II—II of Figure I; and

Figure III is a view similar to Figure II showing a modified form of my invention.

Referring to the drawings in detail, I have not shown a calendering machine in connection with my device as it forms no part of the present invention. The mechanism of the testing device per se is supported and housed in a substantially rectangular frame 1 and comprises a main lever 3

fulcrumed upon a stand 4 which supports a roller 5 adapted to support a strip of fabric 6 to be tested. The nose end of the lever 3 is pivotally connected by means of a stirrup 7 and link 8 to a load-counterbalancing mechanism supported in an upright housing 2, the load-counterbalancing mechanism comprising a pendulum 9 to which is secured an indicating hand 10 adapted to co-operate with a suitably graduated chart 11.

In the operation of the device the fabric is taken from the calendering machine and passed over a series of stationary supporting rollers (not shown) and the roller 5 carried by the lever 3. The weight of the fabric may then be offset or counterbalanced by means of a poise 12 slidably mounted upon a beam 13 carried by the lever 3, and when the poise has been properly positioned the indicator hand 10 will swing into registration with a predetermined point on the chart on the roller 5 in tangency with the plane tangent to the stationary rollers (not shown).

Since the roller 5 supports half the portion of the strip between the stationary rollers, it is evident that any increase in the weight of that part of the strip will depress the roller and any decrease will allow it to swing upwardly. Either movement of the roller will cause the hand 10 to swing away from the central point on the chart and thus indicate a change in weight.

This mechanism is more completely described and claimed in my co-pending application Ser. No. 465,134, filed April 28, 1921.

In the process of coating fabrics, for example, impregnating roofing material, applying rubber to fabric, etc., the coating is usually heated in order that it will adhere to the fabric, and as the coated material comes from the coating machine the coating is soft and plastic and tends to leave the fabric and pile up on or adhere to the rollers. When the coating adheres to the roller 5 it effects an increase in the weight of the roller and results in a change of position of the indicator hand 10, thus erroneously indicating an increase in weight of the coated material when, in fact, a portion of the coating has left the fabric, actually decreasing the weight of the finished product.

In order to obviate the tendency of the coating to adhere to the roller 5 I have pro-

vided a simple and effective means for heating the roller. One end of the roller 5 is provided with a flanged member 15 which is supported in anti-friction bearings 16 carried by the lever 3. The member 15 is also provided with an inwardly protruding annular portion 17 to which is fixedly secured a cylinder 18 of a lesser diameter than that of the roller 5. The exterior surface of the cylinder 18 is coated with porcelain or other suitable insulating material and the cylinder surrounded by a series of heating elements 19. One connection to the heating elements is shown in Figure II. It terminates in a rod 20 which is prevented from contacting with any portion of the flanged member 15 and associated mechanism by means of a porcelain insulator 21. The rod 20 is provided with a rounded head 22 normally contacting with a finger 23 fixed to the lever 3 and connected to a source of electrical energy. The connection at the other end of the roller is substantially identical with the connection just described.

It will be apparent that the finger 23 always remains in contact with the head 22 even during rotation of the roller, as the respective axes of the rod 20 and roller 5 are coincident.

The means supporting the opposite end of the roller 5 corresponds substantially to that hereinbefore described, the lever supporting this end of the roller not being connected to any load-counterbalancing or indicating mechanism.

From the foregoing it will be obvious that when the heating elements are energized the surface of the roller 5 will become heated through radiation of heat from the elements 19 and tend to eliminate the adhering or "piling up" of the coating on the roller.

In the modified form shown in Figure III each end of the roller 5' is fixed to a flanged annulus or ring 15' which is mounted on anti-friction bearings 16' supported upon a member 25'. The member 25' being fixed in the lever 3' is movable only with the lever and does not rotate with the roller 5'.

The cylindrical member 18', which is porcelain or insulated in some suitable manner, supports the heating elements 19' and is secured to the stationary member 25'. With this type of construction the roller may rotate independently of the heating elements and thus decrease the weight which must be supported on the bearings 16', and the heating elements may be directly con-

nected to a source of energy without the interposition of finger contacts, etc.

The embodiments of my invention herein shown and described are to be regarded as illustrative only, and it is to be understood that the invention is susceptible to variation, modification and change within the spirit and scope of the subjoined claims.

Having described my invention, I claim:

1. In a device of the class described, in combination, weighing mechanism, a roller, means operatively connecting said roller to said weighing mechanism, and means for heating the surface of said roller.

2. In a device of the class described, in combination, weighing mechanism including a lever, a roller rotatably supported in said lever, and means for heating said roller.

3. In a device of the class described, in combination, weighing and indicating mechanism, a roller, means connecting said roller to said mechanism whereby said mechanism is moved by movement of said roller, and a heating element contained in said roller.

4. In a device of the class described, in combination, weighing mechanism including a lever, a roller rotatably supported in said lever, and an electrically energized element adapted to heat said roller, said element being rotatable with said roller.

5. In a device of the class described, in combination, weighing mechanism, a roller operatively connected to said weighing mechanism and adapted to support a strip of moving material, and a heating element contained in said roller.

6. In a device for detecting variations in weight per unit of length of a moving strip of material, in combination, a rotatable support for the strip of material, a weighing and indicating device connected to said support, and means for heating said support.

7. In a device for detecting variations in weight of a moving strip of material, a roller for supporting said strip of material, a weight-indicating and load-counterbalancing mechanism connected to said roller, and a stationary heating element contained in said roller.

8. In a device for detecting variations in weight of a moving strip of material, weighing and indicating mechanism including a lever, a roller supported by said lever, and a heating element contained within said roller, said roller being rotatable independently of said heating element.

EDWARD G. THOMAS.
